STOOL OR SIMILAR ARTICLE

Maxwell Yellen, West New York, N. J., assignor to Yellen, Inc., New York, N. Y., a corporation of New York

Application September 23, 1953, Serial No. 26,931

Term of patent 14 years

(Cl. D15—8)

To all whom it may concern:

Be it known that I, Maxwell Yellen, a citizen of the United States, residing at West New York, in the county of Hudson and State of New Jersey,
have invented a new, original, and ornamental Design for a Stool or Similar Article, of which the following is a specification, reference being had to the accompanying drawing, forming part thereof, in which the figure in the drawing is a perspective view of a stool or similar article embodying my new design.

I claim:

The ornamental design for a stool or similar article, as shown.
